UNITED STATES PATENT OFFICE.

CHARLES G. MAHANA, OF THREE RIVERS, MICHIGAN, ASSIGNOR TO SHEFFIELD CAR COMPANY, OF THREE RIVERS, MICHIGAN.

ENGINE-MOUNTING.

1,157,168.

Specification of Letters Patent. Patented Oct. 19, 1915.

Application filed August 9, 1915. Serial No. 44,399.

To all whom it may concern:

Be it known that I, CHARLES G. MAHANA, a citizen of the United States, residing at Three Rivers, Michigan, have invented certain new and useful Improvements in Engine-Mountings, of which the following is a specification.

This invention relates to improvements in engine mountings.

10 My improvements are especially designed by me for embodiment in engines adapted to be mounted on hand cars and the like thus converting them into motor cars and I have shown the same embodied in such a 15 structure in the accompanying drawing although desirable for use in other relation.

The main objects of this invention are to provide an improved mounting for engines by means of which the engine may be adjusted on its base to properly tension the 20 driving belts.

Further objects, and objects relating to details and economies of construction and operation will definitely appear from the 25 detailed description to follow.

I accomplish the objects of my invention by the devices and means described in the following specification. The invention is clearly defined and pointed out in the 30 claims.

A structure constituting a preferred embodiment of my invention is illustrated in the accompanying drawing forming a part of this specification, in which:

35 Figure I is a side elevation of a car embodying the features of my invention. Fig. II is an enlarged detail side view of the base and the fulcrum link for the adjusting lever. Fig. III is a detail horizontal section 40 on the line corresponding to line 3—3 of Fig. II. Fig. IV is a detail end view showing the arrangement of the ways in the base and of the engine slides disposed therein.

In the drawings, similar reference numerals refer to similar parts throughout the several views.

Referring to the drawing 1 represents the platform of a hand car provided with carrying and traction wheels 2. The hand car shown is of the push car type although my improved engine may be readily mounted on a hand car having a gallows frame and walking beam with suitable driving connections.

55 The engine base 3 which is in the nature

of a subbase is provided with attaching bolts 4. The base 3 has longitudinal groove-like facing ways 5 in which the slides 6 on the engine 7 are disposed so as to slidably support the same. The engine is shown in 60 conventional form as its details are not important.

The adjusting lever 8 is pivoted at 9 on the side of the engine and provided with a ratchet 10 coacting with the rack 11 for retaining the lever in its adjusted positions. At its lower end the lever is provided with a laterally projecting fulcrum pin 12. The fulcrum link 13 is pivotally mounted on the 65 engine base at 14 to embrace the lever above 70 its fulcrum pin. The fulcrum link has a series of downwardly facing notches 15 adapted each to receive the fulcrum pin so that it may be shifted. The spring 16 is arranged under the tail end of the link to 75 hold it in engagement with the fulcrum pin.

The fulcrum is adjusted by lifting the fulcrum link to disengage it from the pin and engaging the pin with another notch. This increases the scope of the adjustment of the 80 engine on the base. By sliding the engine upon its base, which may be accomplished by means of the lever 8, the driving belt 17 is tightened or loosened as desired. By providing the adjustable fulcrum for the lever, 85 a considerable scope of adjustment is secured.

My improvements are especially designed by me for use in engines for the driving of motor cars and particularly where the engines are added as an attachment or addition to cars already in use as it obviates the necessity for particular care in setting the engine and may be adjusted to properly tension the driving belt. The embodiment 90 of my improvements illustrated is very simple and practical and the adjustment 95 may be very easily accomplished.

I have not attempted to illustrate or describe various modifications and structural details contemplated by me as I believe the disclosure made will enable those skilled in the art to which my invention relates to embody or adapt the same as conditions 100 may require.

Having thus described my invention, what I claim as new and desire to secure by Letters Patent is:—

1. In a structure of the class described, the combination with an engine, of a base 110

- having facing groove-like ways therein, said engine having slide members disposed in said ways whereby the engine is slidably supported on the base, a lever mounted on 5 said engine and provided with a laterally projecting fulcrum pin at its lower end, a retaining ratchet for said lever, a yoke-like fulcrum link pivotally mounted on said base to embrace the lower end of said lever 10 above its fulcrum pin and having a plurality of downwardly facing notches therein adapted to receive said fulcrum pin, and a spring acting on said fulcrum link to hold it in engagement with said pin.
- 15 2. In a structure of the class described, the combination with an engine, of a base on which said engine is adjustably mounted, a lever mounted on said engine and provided with a laterally projecting fulcrum 20 pin at its lower end, a retaining ratchet for said lever, a yoke-like fulcrum link pivotally mounted on said base to embrace the lower end of said lever above its fulcrum pin and having a plurality of downwardly 25 facing notches therein adapted to receive said fulcrum pin, and a spring acting on said fulcrum link to hold it in engagement with said pin.
- 30 3. In a structure of the class described, the combination with an engine, of a base on which said engine is mounted for adjustment, a lever pivotally mounted on said

engine, said lever being provided with means for retaining it in its adjusted positions and having a laterally projecting pin 35 at its lower end, a fulcrum link pivotally mounted on said base and having a plurality of notches therein adapted to receive said pin, and a spring for holding said link in engagement with said pin.

4. In a structure of the class described, the combination with an engine, of a base on which said engine is mounted for adjustment, a lever pivotally mounted on said engine and provided with means for retaining it in its adjusted positions, a fulcrum pin on said lever, and a fulcrum link mounted on said base, said fulcrum pin being adjustably engaged with said link.

5. In a structure of the class described, the combination with an engine, of a base on which said engine is mounted for adjustment, a lever pivotally mounted on said engine and provided with means for retaining it in its adjusted positions, a fulcrum 50 pin on said lever, and a fulcrum link mounted on said base.

In witness whereof, I have hereunto set my hand and seal in the presence of two witnesses.

CHARLES G. MAHANA. [L.S.]
